OSCAR HAMMERSTEIN, OF NEW YORK, N. Y.; EMMA SWIFT HAMMERSTEIN, EXECUTRIX OF SAID OSCAR HAMMERSTEIN, DECEASED, ASSIGNOR TO EMMA SWIFT HAMMERSTEIN, OF NEW YORK, N. Y.

SUSPENDERS.

1,360,290.

Specification of Letters Patent. Patented Nov. 30, 1920.

Application filed October 4, 1918. Serial No. 256,812.

To all whom it may concern:

Be it known that I, OSCAR HAMMERSTEIN, a citizen of the United States, and resident of the borough of Manhattan, city, county, and State of New York, have invented certain new and useful Improvements in Suspenders, of which the following is a specification.

My invention relates to suspenders and has for its object to provide an arrangement in which the supporting members are of permanent length and in which the necessary adjustment is obtained by means of a plurality of fastening devices such as buttonholes. My invention contemplates further a construction in which the supporting members and the relative positions of the buttonholes or equivalent devices thereon are arranged so that the trousers will not be distorted or folded at the waist line. A further object of my invention is to avoid the use of metallic elements of any kind and to make the suspenders of a material which is washable and capable of being laundried. My invention will be fully described herein-after and the features of novelty will be pointed out in the appended claim.

In the accompanying drawings, Figures 1 and 2 show two specific embodiments of my invention for illustrative and descriptive purposes.

As shown in the drawings the suspenders comprise the members 5 continued at the back in the form of rear supporting members or tabs 6, the latter being formed by crossing and connecting the members 5 at the proper point or in any other suitable manner. At the front the members 5 are each combined with a pair of front supporting members or tabs, those in the form shown in Fig. 1 and indicated as 7 and 8 diverging from points on the members 5 which come close to the shoulders when the suspenders are worn while the members or tabs shown in Fig. 2 and designated as 9 and 10 diverge from points near the waist line of the wearer. The diverging front members or tabs, 7, 8 and 9, 10 may comprise integral continuations of the members 5 or may be otherwise combined therewith.

The entire suspenders in either form are constructed of washable materials, such as cotton, linen, silk or other fabrics commonly termed non-elastic or a combination of such

materials. In the preferred construction a plurality of layers of material are combined and sewed together with multiple rows of stitches to impart a maximum strength to the suspenders and to obviate stretch or at least reduce it to a minimum; single ply tape of suitable thickness has been found to also provide a satisfactory construction. In whatever form the suspenders are constructed, the various members and tabs constituting the device have permanent fixed lengths which do not change to any material extent, the dimensions being such as to adapt the suspenders to the widest range of use.

In order to provide for an adjustment of the suspenders to meet the requirements or desires of different individuals, at least some of the tabs or all of them if desired are provided with a plurality of fastening devices such as, for instance, buttonholes. The illustrated examples show the front tabs 7, 8 and 9, 10 each provided with a series of buttonholes 11 and 12 located in spaced relation to each other on said tabs, the buttonholes 11 being formed in the tabs 7 and 9 while the buttonholes 12 are in the tabs 8 and 10. In the preferred construction the buttonholes 11 are offset with respect to the buttonholes 12 in directions lengthwise of the tabs, or in other words are located at points somewhat higher than the location of said buttonholes 12, the location being computed with respect to the waist line of the trousers. With this arrangement when the suspenders are being worn, the coöperative engagement of the buttonholes 11 and 12 with the buttons on the trousers is such that the tabs 7, 8 and 9, 10 are all and each of them under the proper tension and performing their share of the work in properly sustaining the trousers in position.

In other words the suspender has an inner and outer section on both the right and left side; the inner sections, comprising the tabs 10 hang approximately straight from the shoulder, when the suspender is worn, while the outer sections, comprising the tabs 11, when fastened to the trouser button are pulled somewhat to the side in a direction corresponding to the direction of the waist line of the trousers. By having the buttonholes 11 higher than the buttonholes 12 the trouser is caused to hang or set in a substantially straight line. With the buttonholes

11 and 12 arranged in transverse registry the supporting strain would be transmitted entirely to the tabs 8 and 10, the tabs 7 and 9 in such case being slack and performing no supporting function. It will be understood that the tabs 7 and 9 may be made somewhat shorter than the tabs 8 and 10 or that the tabs of each pair may be of the same length.

10 By connecting the proper buttonholes of the front tabs with the buttons on the trousers any desired adjustment within the range of the suspenders may be secured and the trousers may be readily raised and lowered 15 as desired. In some cases the rear tabs may be provided with a plurality of buttonholes, in which case the front tabs may each have a single buttonhole or a series as desired. Nevertheless the buttonhole of the outer section will have to be higher than the one on the inner section. With present day trousers, at least in the majority of cases, the buttons are on the inside of the waist band so that any depending portions of the front 25 or rear tabs may be tucked within the trousers so as to be invisible.

To make it certain that the suspenders are properly put on and to secure the desired co-operation between the proper buttonholes 30 11 and 12 with the proper trouser buttons or, in other words, to properly position the front tabs 7, 8 or 9, 10, and to facilitate the placing and adjustment of the inner and outer sections, I prefer to place an indicating 35 mark or other suitable device 13 upon the suspenders preferably at the rear where the members 5 cross; the device 13 may be located upon either the inside or outside surface of the suspenders and in either case 40 will readily indicate the proper way in which the suspenders are to be worn to secure the desired results.

My improved suspenders absolutely avoid the use of any metallic elements, are fixed 45 and positive in adjustment and action and do not yield or stretch to any appreciable extent; the suspenders are economical to manufacture and may easily be maintained in a sanitary and clean condition by washing 50 and laundrying.

The strains are equally distributed upon

the wearer and in the form shown in Fig. 1 are transmitted entirely to the shoulders because of the arrangement of the tabs 7 and 8, this form also avoiding a distortion or 55 folding of the trousers along the waist line and particularly between the buttons to which each pair of tabs 7, 8 are attached. The offset arrangement of the buttonholes of each pair of tabs, in addition to its other 60 advantages, evenly distributes the strains over the trousers and keeps it absolutely straight about the waist of the wearer, instead of pulling it up at one point and permitting it to sag at another, as is very often 65 the case in existing constructions. Once the wearer decides on the proper adjustment for a given pair of trousers the same result may be obtained repeatedly and without change 70 by simply always connecting the same buttonholes with the trouser buttons.

Various changes in the specific constructions shown and described may be made within the scope of the claim without departing from the spirit of my invention.

I claim:—

A suspender of the kind described, comprising continuous members of substantially non-elastic fabric terminating at one end in front tabs comprising integral portions of 80 said continuous members, the latter being crossed at the back and permanently connected together to form rear tabs comprising integral continuations of said members, said rear tabs being each provided with at least 85 one buttonhole, and continuous members of substantially non-elastic fabric permanently secured by stitching to the said first continuous members and diverging therefrom at points located in the neighborhood of the 90 shoulders when the suspenders are worn, to form additional front tabs complementary to the front tabs first mentioned, said front tabs each being provided with a plurality of button holes, the button holes of one tab of 95 each pair being off-set in the direction of the length of said tabs with respect to the button holes of the other tabs of said pair.

In testimony whereof I have hereunto set my hand.

OSCAR HAMMERSTEIN.
